UNITED STATES PATENT OFFICE.

LAWRENCE J. MEAD, OF DARIEN, CONNECTICUT.

AUTOMATIC LUBRICATOR.

1,188,470.

Specification of Letters Patent. Patented June 27, 1916.

Application filed July 15, 1914. Serial No. 851,084.

To all whom it may concern:

Be it known that I, LAWRENCE J. MEAD, a citizen of the United States, and resident of Darien, in the county of Fairfield and State of Connecticut, have invented an Improvement in Automatic Lubricators, of which the following is a specification.

The operation of elevator cars requires the use of devices for automatically applying lubricant to the slideways of the car or 10 to the counter-weights thereof. Devices of this character heretofore used fed lubricants to all portions of the slideways, including the portions already well lubricated.

15 The present invention is designed to feed lubricants to the slideways only when and where needed, and comprehends lubricating means controlled by the friction developed or lost by a friction shoe in passing along 20 the slideway, whereby lubricant is applied whenever the movement of the friction shoe is retarded on account of increased friction at an insufficiently lubricated portion, and is discontinued whenever the normal movement 25 of the shoe is resumed as it reaches a well lubricated portion of the slideway.

One form of the device is illustrated in Fig. 1 in a side elevation, some of the parts being broken away; Fig. 2 is a top view of 30 the device shown in Fig. 1; Fig. 3 is a vertical cross section along the line A—A of Fig. 1; Fig. 4 a similar view along the line B—B of the same figure; Fig. 5 a side elevation of a modification of the invention, 35 and Fig. 6 a horizontal cross section along the line C—C of Fig. 1.

The carrying parts, as for instance, an elevator car or the counter-weights thereof, are indicated at 1 and the slideways of the 40 elevator shaft at 2. A frame 3 is arranged on the top of the carrying parts for supporting a lubricant container 4, the latter provided with an outlet 5, having a valve 6 adapted to control the flow of lubricant 45 from the container into a distributing box 7. A pair of nozzles 8 direct the lubricant into a swab-pan 9 preferably provided with a swab or felt 10, or other suitable material, the pair being supported by means of a 50 bracket 11.

The valve 6 is controlled by means of a rod 12 having near its upper end a pair of operating collars 13 and 14. The lubricant container 4 is provided with a pair of 55 brackets 15 and 16 supporting a shaft 17. A forked lever 18 is pivotally secured to the

shaft 17 by means of a helical hub 19. A sheet metal frame carried by the lever 18, comprises a base 20 having openings 21 and 21', and upwardly extending lugs 22 and 23. 60 An extension 24 of the base 20 of the sheet metal frame is arranged on one side thereof. The branches of the forked lever 18 are provided with helical springs 25 and 26 bound on one side by the lugs 23 of the sheet metal 65 frame and on the other side by suitable lugs 27 of the frictional contact member 28.

The lubricant container 4 carries a vertical bolt 29, secured in a boss 30 and having a horizontally protruding pin 31. Helical 70 springs 32 and 33 are provided on the bolt 29, so that one of the springs is located between the boss 30 and the lower side of the base 20 of the sheet metal frame, while the second spring 32, is located between the 75 upper side of the base 20 and a holding nut 34 at the upper end of the bolt 29. The lubricant container further carries a double armed lever 35 pivoted in brackets 36, secured to the container. The inner end 37 of 80 the lever 35 is provided with an opening for engaging the valve rod 12 below the collar 13.

Fig. 5 illustrates a modification of the invention in which 38 indicates a bracket for 85 carrying a resilient arm 39, having an elongated opening 40 for engaging a vertical bolt 41 secured to the lubricant container. The upper end of the bolt is provided with a collar 42. Helical springs 32, 33 are provided, one on each side of the resilient arm 39, one resting against one face of the arm and the lubricant container and the other against the other face of the arm and the collar 42. The resilient arm 39 extends 90 into a bent portion 43 and a curved end 44, the latter adapted to engage a suitable pin 45, on lugs 27, of the frictional shoe 28. Both forms of the invention shown in the 95 figures of the drawings illustrate the pin 100 31 passing through the bolt 29 in about the plane of either the base plate 20 of the supporting frame (Fig. 3) or the bent arm 39 (Fig. 5). This pin 31 serves as a peculiar separating means between the helical springs 32 and 33, for the purpose of removing the pressure of the springs in normal position on either the base plate 20 or the bent arm 39. It will be noted that 105 a slot in the base plate and the bent arm 110 respectively permits movement of both of the latter toward and from either side of

the pin 31. The lowest portion of the spring 32 and the highest portion of the spring 33, form a horizontal ring contacting directly, one on each side of and with the pin, so that the base plate as well as the bent arm, are practically free from pressure of the spring in either direction when in normal position. In case, however, of the displacement of the friction shoe in relation to the lubricant container, the base plate or the bent arm will cause compression of either of the helical springs, without however, being aided in doing so, by the other spring.

15 In the operation of this invention, the movement of an elevator car, or an equivalent moving member such as the cross head of a reciprocating engine or pump, has the effect of retarding the movement of the 20 friction shoe, wherever an unlubricated or rough portion of the surface of the slideway causes an increase of friction between the shoe and the slideway.

Referring to Fig. 1, the retarding of the 25 friction shoe 28, if the elevator car is moving upwardly, causes a downward movement of the lever 18 and the sheet metal frame secured thereto, a depression of the helical spring 33 and, therefore, pressure of the 30 extension 24 of the base 20, upon the outer arm of the lever 35. The inner end of the lever 35 is thereby raised and presses against the collar 13 of the valve stem 12 and opens the valve 6, so that lubricant may flow 35 through the nozzles 8, 8, unto the lubricating swab 10. In case the moving element moves in the opposite direction, so that the retarded movement of the friction shoe 28 causes an upward movement of the lever 18, 40 then the helical spring 32 becomes compressed, and the extension of the base plate 20, having the opening 21', engages the collar 14 of the valve stem 12, and again causes the opening of the valve 6, resulting 45 in the delivery of the lubricant.

The modification illustrated in Fig. 5 operates in a similar way, so that in case of a retarded movement of the friction shoe 28, toward the lubricant container, the extension 24 depresses one end of the lever 35, causing the lifting of the other end of the lever in contact with the collar 13 of the valve stem, and the retarded movement of the friction shoe in the opposite direction 55 causes the direct lifting of the collar 14 of the valve stem in contact with the bent portion 43 of the resilient arm 39.

It will be apparent that the invention is applicable not only to lubricating devices 60 for elevator cars, but to any kind of apparatus moving along a slideway and requiring lubrication.

What I claim is:

1. The combination with a slideway of a 65 normally inoperative lubricating device, and

means frictionally engaging said slideway to actuate said device by increase of friction between said frictional means and slideway.

2. The combination with a slideway of a 70 normally inoperative lubricating device and means for moving the same along said slideway, said device being adapted to go into operation whenever increased frictional resistance between it and the slideway is developed owing to lack of lubrication of the latter. 75

3. The combination with a slideway of an 80 elevator car, a normally inoperative lubricating device, and means for moving said device along said slideway, said device being adapted to go into operation whenever retarded by increase of friction between it and said slideway due to insufficient lubrication of the latter. 85

4. The combination with a slideway of an 85 elevator car, a lubricant container connected to said car, and normally inoperative lubricating means associated with said lubricant container and said slideway, said means 90 being adapted to go into operation whenever increased frictional resistance is developed between it and said slideway due to insufficient lubrication of the latter.

5. The combination with a slideway of an 95 elevator car, a lubricant container connected to said car, and normally inoperative lubricating means, including a friction shoe, associated with said lubricant container and said slideway, said means being adapted to 100 go into operation whenever increased frictional resistance is developed between said friction shoe and the slideway due to insufficient lubrication of the latter.

6. The combination with a slideway of a 105 car and a normally inoperative lubricating device, including a lubricant container having a discharge valve and a friction shoe movable along said slideway, said lubricating device being adapted to go into operation 110 whenever said friction shoe is retarded by increase of friction between it and said slideway due to insufficient lubrication of the latter.

7. The combination with a slideway, of a 115 friction shoe adapted to be retarded in its movement when passing over unlubricated portions of the surface of said slideway only, means for moving said shoe, means connected with said shoe for applying lubricant to such unlubricated portions when the movement of said shoe is so retarded, and means for stopping the flow of lubricant when said shoe has passed such unlubricated portions. 120

8. The combination with an elevator 125 slideway, of a car, a lubricant container movable with said car along said slideway, an outlet on said container, a valve in said outlet, a valve stem, a friction shoe mov- 130

able along said slideway, means for operating said valve stem when said shoe passes over unlubricated portions of the surface of said slideway, and means for operating 5 said valve stem when said shoe has passed such unlubricated portions.

9. The combination with a slideway of a lubricant container movable along the slideway, another movable member engaging 10 said slideway and connected to said container and adapted to have reciprocatory movements in opposite directions relative to said container, means connected to said movable member and container for applying 15 lubricant to said slideway on any such relative movement of said movable member, and yielding means for maintaining said movable member in equilibrium between such opposite movements.
10. The combination with a slideway of a lubricant container movable along the slideway, a friction shoe engaging said slideway and connected to said container and adapted to have reciprocatory movements in opposite directions relative to said 20 container, means connected to said shoe and container for applying lubricant to said slideway on any such relative movement of said shoe and yielding means exerting opposite forces for maintaining said shoe in equilibrium between said movements.
11. The combination with a slideway of a lubricant container movable along the slideway, a friction shoe engaging said 25 slideway and connected to said container and adapted to have reciprocatory movements in opposite directions relative to said container, means connected to said shoe and container for applying lubricant to said 30 slideway on any such relative movement of said shoe and yielding means exerting opposite forces for maintaining said shoe in equilibrium between said movements.

Signed at New York, in the county and 45 State of New York, this 29th day of June, 1914.

LAWRENCE J. MEAD.
